UNITED STATES PATENT OFFICE.

ADOLPHUS W. GREELY, OF WASHINGTON, DISTRICT OF COLUMBIA.

TELEGRAPH AND CABLE CODE.

SPECIFICATION forming part of Letters Patent No. 678,363, dated July 16, 1901.

Application filed August 1, 1900. Serial No. 25,577. (No model.)

To all whom it may concern:

Be it known that I, ADOLPHUS W. GREELY, brigadier-general and chief signal officer United States Army, residing at Washington, 5 District of Columbia, have invented certain new and useful Improvements in Telegraph and Cable Codes, of which the following is a description.

The object of my invention is to use telegraphically characters of the present telegraph and cable alphabets in such order of arrangement as to insure the maximum rate of transmission and the minimum chance of errors, omissions, &c.; and a further object is 15 to construct from such characters so arranged, classes of code-words, each containing an equal number of letters, the class of words of shorter length being used for the largest proportion of telegraphic traffic, thus producing 20 a telegraph and cable code superior in character to any heretofore developed.

It is well understood that in the present cable alphabet some of the letters—such as “m,” (//,) “o,” (///,) and “h” (\\\\\\)—require successive signals of the same sign in their construction, whereas others—such as “a,” (\\,) “r,” (\\\\,) and “k” (/\\)—are made up of successive signals of opposite sign, while others still—such as “l” (\\\\\\) 25 and “y” (/\\\\)—are made up of different combinations of signals of opposite sign, in which, however, there are successive signals of the same sign.

It has been determined by actual trial that 35 from an electrical standpoint those letters which are wholly made up of successive signals of opposite sign are superior telegraphically to either of the other two classes above mentioned, and also that in the case of consecutive letter combinations those combinations are most effective in which the first signal of the succeeding letter is of opposite sign to the last signal of the preceding letter. The theoretically-perfect alphabet is made up of 40 successive signals produced by plain sign-wave alternating current, in which the cable is alternately charged and discharged in a perfectly regular manner.

It is the object of this invention to employ 45 these principles deduced from actual experiment in the make-up of individual characters

and combinations of characters into code-words.

In carrying out my invention I make use of those letters of the present telegraph and cable alphabet now in use which are made up of successive signals of opposite polarity—that is, in the telegraph-alphabet made up of dot following dash or dash following dot, and in the cable-alphabet a swing to the right following a swing to the left, and a swing to the left following a swing to the right—and I combine such letters into a series of code-words conforming to the international telegraphic rules, which require that words of definite meaning and of presented languages must be used. The code-words so made up will, by reason of the fact that they are made up of successive signals of different polarity, be transmitted with the least possible chance for 60 errors and with the greatest possible speed, and in order to reduce, as far as possible, the chance of error in transmission as well as to facilitate the speed of transmission I arrange the code-words thus made up into special series, according to the number of letters in the words.

The code-words now generally in use average from eight to nine letters. I substitute for these code-words special series of code-words consisting of three letters each, four letters each, five letters each, and six letters each, the words selected being of the character above mentioned—that is, made up of letters in the formation of which successive signals 80 of different sign are used.

Examples illustrating the several special series of code-words are as follows:

Three-letter words.	Four-letter words.	Five-letter words.	Six-letter words.	90
act	cent	cater	canker	
art	area	crate	tinker	
and	cake	enter	twenty	
ate	wand	track	winter	
end	karn	treat	writer	
ear	tree	under	turned	
ken	tank	trend	tended	
tea	tart	wreak	wended	
ten	wart	creak	mended	
wet	mate	smart	create	
wen				95
				100

The three-letter code will be applied, so far as possible, to that class of cable business

which not only demands the highest possible speed, but also comprises the greatest percentage of the cable business. It will be especially applicable to the interchange of stock business between great financial centers—such as London, New York, Paris, Berlin, and Rotterdam—in which speed and accuracy are of the utmost importance. For this class of business the gain in speed of transmission by the use of my code is apparent when a cablegram of, say, ten words of my three-letter code is compared with an ordinary code-message of ten eight-letter words. It is evident that the three-letter-code message could be transmitted and received in much less than half the time. The three-letter code could also be used between bankers and others for special purposes where speed and accuracy are of importance. The four-letter code and the five-letter code may be used in sequential order for less expensive class of cable business and the six-letter code for still less expensive business.

A very great advantage which results from thus dividing the general code into special codes of respectively three, four, five, and

25 A very great advantage which results from thus dividing the general code into special codes of respectively three, four, five, and six letters is that greater certainty as to the receipt in correct form of the message transmitted is insured. For instance, when a
30 banker uses with his correspondents the four-letter code he would know that a word of five letters or three letters in a message delivered to him must be an error. So, too, where the five-letter code is used a word containing
35 either less than or more than five letters will at once be recognized as an error.

A further feature of my invention is the provision of means for transmitting by a single code-word three or even four sets of even 4° code-numbers from zero to ninety-eight. In carrying out this feature of my invention I use the vowels A, E, I, O, and U or Y to represent, respectively, the even unit figures from 0 to 8, (A=0, E=2, I=4, O=6, and U 45 or Y=8,) and nine selected consonants, C, D, F, K, L, N, R, T, and W, to represent figures having the value of tens. (C=10, D=20, F=30, K=40, L=50, N=60, R=70, T=80, and W=90.) It will be observed that 5° so far as possible I make use in this feature of my invention of the successive signals of

opposite sign, which forms the main feature of the invention of this application. It will also be observed that the vowels and consonants used are arranged in alphabetical sequence, this arrangement being calculated to facilitate translation by memory. 55

The absence of any figure having the value of ten is indicated by the use of any consonant other than one of the nine selected, or in the beginning of a word by the absence of any consonant, the assigned unit vowel standing first in the word. By suitable combinations two or more sets of such even code numbers can be sent by a single code-word. For example:

Care ($\checkmark\checkmark\backslash\checkmark\checkmark\backslash$) = 10.72.

Dine ($\backslash\backslash\backslash\backslash\backslash$) = 24.62.

$$\text{Caralis } (\sqrt{\sqrt{\sqrt{\sqrt{\sqrt{70-54}}}}}) = 10 \cdot 7^0$$

Having thus described my invention, what I claim, and desire to secure by Letters Patent, is—

1. In a telegraph and cable code, a code-word consisting of letters made up of successive signals of opposite polarity; substantially as described.

2. In a telegraph and cable code, a series 85 of code-words each having the same number of letters and each consisting of letters made up of successive signals of opposite polarity; substantially as described.

3. In a telegraph and cable code, an even 90
code-number system, in which the even units
from zero to eight are represented respec-
tively by a vowel and the tens from ten to
ninety are represented by consonants made
up of successive signals of opposite sign; sub- 95
stantially as described.

In testimony whereof I affix my signature
in presence of two witnesses.

ADOLPHUS W. GREENEY.

Witnesses:

GEORGE O. SQUIRE,
EUGENE O. FECHÉT.
